UNITED STATES PATENT OFFICE.

BERNARD C. McENTEE AND LOUIS H. CONSTANT, OF WICHITA FALLS, TEXAS.

SHOE TONGUE AND FASTENER.

Application filed March 25, 1926. Serial No. 97,343.

This invention relates to shoes and more particularly to a combined tongue and fastener for the shoe.

One object of the invention is to provide a device which in addition to serving as a tongue will also serve to latch the shoe and eliminate laces.

Another object of the invention is to so construct the combined tongue and fastener that it may be employed in connection with a high or low shoe of a conventional construction.

This invention is illustrated in the accompanying drawings, wherein—

Fig. 1 is a perspective view showing the improved tongue and fastener applied to a high shoe;

Fig. 2 is an enlarged transverse sectional view taken on the line 2—2 of Fig. 1;

Fig. 3 is a fragmentary sectional view taken on the line 3—3 of Fig. 1;

Fig. 4 is a view of the tongue and fastener before being applied to the shoe;

Fig. 5 is a perspective view illustrating a combined tongue and fastener of a slightly modified construction applied to a shoe having lace-engaging hooks as well as eyes;

Fig. 6 is an enlarged transverse sectional view taken on the line 6—6 of Fig. 5;

Fig. 7 is a longitudinal sectional view taken on the line 7—7 of Fig. 5, and

Fig. 8 is a plan view of the combined tongue and fastener before being applied to the shoe.

In Fig. 1, a tongue and fastener formed as shown in Fig. 4 has been applied to a shoe which is of a conventional construction and indicated in general by the numeral 1. This shoe is of the type known as a high-shoe and includes a vamp 2 and top 3, the edge portions of which are spaced from each other and provided with eyes 4. The eyes 4 are spaced longitudinally of the top from the vamp to the upper edge of the top and are ordinarily intended to receive a shoe lace.

The tongue 5 which forms the subject-matter of this invention is of such length and width that when its lower end is stitched to the under face of the vamp 2 its upper end will terminate substantially even with the upper edge of the top 3 and its side portions will extend in underlying relation to the spaced side edge portions of the top, as shown in Fig. 2. Fastener elements or studs 6 are secured to the tongue 5 in spaced

relation to each other longitudinally of the tongue and adjacent its side edges. These studs are in such spaced relation to each other that, when the shoe is worn, the sides of the top may be moved into overlapping relation to the tongue and the studs 6 passed outwardly through the eyes 4 with their headed free ends projecting from the eyes. After the studs have been passed through the eyes, the strips 7 which project from the upper end of the tongue are folded downwardly and the fastener elements or sockets 8 carried by the strips are snapped into engagement with the heads of the studs. Therefore, the strips will be securely but releasably held in engagement with the studs and the shoe retained closed. It should be also noted that since the tongue carries studs which project through the eyes of the shoe it will be prevented from slipping out of place and cannot become crumpled in the shoe and cause the shoe to be uncomfortable.

When it is desired to remove the shoe, it is merely necessary to draw the strips 7 upwardly and outwardly out of engagement with the studs and the top will be released from the tongue. It will be, of course, understood that if so desired only one of the strips 7 may be released when removing the shoe and the other strip left in engagement with the cooperating studs of the tongue. A combined tongue and fastener, such as shown in Fig. 4, could also be applied to a low-quartered shoe but the tongue and its cooperating strips would, of course, have to be shorter than the one employed in connection with a high-shoe.

The tongue and fastener shown in Fig. 8 is for use in connection with a shoe of the type shown in Fig. 5. The shoe, which is indicated in general by the numeral 9, is similar to that shown in Fig. 1 but instead of having its top 10 provided with lace-receiving eyes throughout its entire height it has its upper portion provided with hooks 11 so that after a shoe lace has been passed through eyes in the lower portion of the top the lace may be engaged with the hooks in a well known manner. The tongue 12 which is employed in connection with this type of shoe is shorter than the tongue 5 as it is only to extend from the vamp 13 to which its lower end is secured to approximately the upper lace-receiving eye of the shoe. Studs 14, which correspond to the studs 6, are carried by the tongue 12 and are adapted to be

passed through the eyes of the shoe top and engaged with the sockets 15 of the strips 16 which are carried by the tongue and correspond to the strips 7. Notches 17 are formed 5 in the sides of the tongue 12 adjacent its upper end to receive portions of the shoe top when the sides of the shoe top are moved into overlying relation to the tongue and the strips 16 folded downwardly and secured, as 10 shown in Fig. 5. In order to secure the portion of the shoe having the hooks 11, there has been provided a tongue extension 18 which is of sufficient width to fit between the strips 16 and have its lower end secured to 15 the upper end of the tongue 12 by a fastener 19. The fastener 19 may serve to permanently connect the tongue extension with the tongue or it may consist of a stud 20 carried by the tongue and a cooperating socket 21 carried by the tongue extension and snapped 20 into engagement with the stud 20. The tongue extension is of sufficient length to extend from the tongue 12 to the upper edge of the shoe top and of sufficient width to 25 overlap the spaced sides of the shoe top, as shown in Fig. 6. Latch strips 22 which may be formed of metal or any other suitable material are secured against the outer face of the tongue extension and extend from 30 the sides thereof. The extended ends of the latch strips are formed with keyhole openings 23 of sufficient size to receive the heads of the hooks 11. By having the latch strips formed with keyhole openings they 35 may be engaged with the hooks at one side of the shoe top and then engaged with the hooks at the other side of the shoe top and the upper portion of the shoe top will be securely held closed but may be easily released when necessary.

Having thus described the invention, we claim:

1. A shoe including a top having spaced edge portions provided with eyes, a tongue 45 to extend beneath the spaced edge portions of said top in underlying relation to the eyes, a portion of said tongue being adapted to be disposed in overlying relation to the eyes of said top, and fasteners adapted to be passed through said eyes and releasably connect the overlying and underlying portions of said tongue.

2. A shoe including a top having spaced 55 edge portions provided with eyes, a tongue to extend beneath the spaced edge portions of said top in underlying relation to the eyes, a portion of said tongue being adapted to be folded downwardly in overlying relation to the eyes, and cooperating interengageable fasteners carried by the overlying and underlying portions of the tongue, certain of said fasteners being passed through the eyes when interengaged with the other fasteners.

3. A shoe including a top having spaced

edge portions provided with eyes, a tongue adapted to extend between and beneath the spaced edge portions of said top, strips for covering said eyes, and cooperating fasteners carried by said tongue and strips, certain of 70 said fasteners being passed through said eyes when interengaged with the other fasteners.

4. A shoe including a top having spaced edge portions provided with eyes, a tongue 75 adapted to extend between and beneath the spaced edge portions of said top, strips carried by said tongue for extending in overlapping relation to the said edge portions, and cooperating interengageable fasteners 80 carried by said tongue and strips, certain of said fasteners being passed through said eyes when interengaged with the other fasteners.

5. A shoe including a top having spaced edge portions provided with eyes, and a combined tongue and fastener including a portion extending between and beneath the spaced edge portions of the shoe top and provided with fastener elements, and a portion adapted to extend in overlying relation to the eyes and provided with fastener elements to interengage with the first-mentioned fastener elements, certain of said fastener elements being passed through said eyes when interengaged with the other fastener elements.

6. A shoe including a top having spaced edge portions provided with eyes, a tongue adapted to extend between and beneath the spaced edge portions of said top, strips connected at their ends with the upper end of said tongue and adapted to be extended downwardly in covering relation to said eyes, and cooperating interengageable fastener elements carried by said strips and tongue, 105 certain of said fastener elements being passed through the eyes when interengaged with the other fastener elements.

7. A combined tongue and shoe fastener comprising a tongue, fastener elements 110 spaced longitudinally of the tongue adjacent the sides thereof, strips adapted to be disposed in overlying relation to lacing eyes of a shoe top, and fastener elements carried by said strips and interengageable with the 115 first-mentioned fasteners with certain of the fasteners passed through the eyes of the shoe.

8. A combined tongue and shoe fastener comprising a tongue, fastener elements spaced longitudinally of the tongue adjacent the sides thereof and adapted to be passed outwardly through lacing eyes of a shoe top, strips connected at their ends to the upper end of said tongue and adapted to be folded downwardly into overlying relation 125 to the lacing eyes of the shoe, and fastener elements carried by said strips to engage the fastener elements of said tongue and retain the same in the lacing eyes.

9. A combined tongue and shoe fastener 130

- comprising a tongue, fastener elements spaced longitudinally of the tongue adjacent the sides thereof, strips carried by said tongue and adapted to be disposed in overlying relation to lacing eyes of a shoe top, fastener elements carried by said strips and interengageable with the first-mentioned fasteners with certain of the fasteners passed through the eyes of the shoe, and an extension carried by said tongue and extending upwardly therefrom and adapted to be releasably connected with lace-engaging hooks of a shoe. 5
10. A combined tongue and shoe fastener comprising a tongue, fastener elements spaced longitudinally of the tongue adjacent the sides thereof, strips carried by said tongue and adapted to be disposed in overlying relation to lacing eyes of a shoe top, fastener elements carried by said strips and interengageable with the first-mentioned fasteners with certain of the fasteners passed through the eyes of the shoe, an extension secured to the upper end of said tongue and extending upwardly therefrom, and fasteners carried by said extension and extending transversely thereof and adapted to be removably engaged with lace-engaging hooks of the shoe top. 20
- 25
30. 11. A combined tongue and shoe fastener comprising a tongue, fastener elements spaced longitudinally of the tongue adjacent the sides thereof, strips carried by said tongue and adapted to be disposed in overlying relation to lacing eyes of a shoe top, fastener elements carried by said strips and interengageable with the first-mentioned fasteners with certain of the fasteners passed through the eyes of the shoe, and extension secured to the upper end of said tongue and
- 35
- 40
- extending upwardly therefrom, and fasteners carried by said extension and projecting from its sides and formed with openings to receive lace-engaging hooks of the shoe top to releasably connect the fasteners therewith. 45
12. A shoe including a top having spaced edge portions provided with openings, a tongue adapted to extend between and beneath the spaced edge portions of said top, strips for covering the openings in the spaced edge portions, and fasteners for releasably connecting said strips with said tongue including portions adapted to be inserted through the openings. 50
13. A combined tongue and fastener for shoes and the like comprising a tongue adapted to extend between and beneath separated edge portions of apertured parts to be connected, strips adapted to be disposed in overlying relation to the said edge portions in covering relation to the apertures thereof, and fasteners adapted to be passed through said apertures and releasably connect said tongue and strips. 55
14. A combined tongue and fastener for shoes and the like comprising a tongue adapted to extend between and beneath separated edge portions of apertured parts to be connected, strips adapted to be disposed in overlying relation to the said edge portions in covering relation to the apertures thereof, and fasteners carried by the side portions of said tongue and adapted to be passed outwardly through the apertures and releasably connected with said strips. 60
- 70
- 75
- In testimony whereof we affix our signatures.
